UNITED STATES PATENT OFFICE

2,520,839

BOILER

William J. Huie, Philadelphia, Pa.

Application August 23, 1946, Serial No. 692,593

6 Claims. (Cl. 122—277)

1

This invention relates to new and useful improvements in hot water and steam boilers and more particularly to boilers especially adapted for use in heating homes and other relatively small buildings of a similar nature.

One object of the present invention is to provide a boiler of novel construction for hot water or steam heating purposes which is of the down-draft type and embodies means for cooling the combustion gases passing to the stack to thereby lower the stack temperature while at the same time effectively pre-heating the water entering and returning to the boiler for reheating and recirculation.

Another object of the invention is to provide a boiler of the character set forth having a novel combustion chamber or fire box operable to effect substantially complete combustion of fuel oil in confinement with a minimum supply of secondary air or oxygen.

Another object of the invention is to provide a novel boiler construction as set forth which is fabricated entirely of steel welded together and weighing approximately fifty per cent less than other boilers of similar capacity.

A further object of the invention is to provide a novel boiler having the features described which is constructed and arranged so that additional heating surface and water capacity may be added as required without increasing the size and dimensions of the boiler.

A still further object of the invention is to provide a boiler of the character set forth embodying a water baffle and a boiler make-up water heater of distinct and novel construction and design.

Still a further object of the invention is to provide a boiler having the structural and operating features and characteristics set forth which is of relatively simplified and inexpensive construction and highly economical and efficient in operation and use.

These and other objects of the invention and the various features and details of the construction and arrangement thereof are hereinafter fully set forth and described and shown in the accompanying drawing, in which:

Fig. 1 is a perspective view partially in section showing certain of the features and details of a boiler made according to the present invention.

Fig. 2 is a vertical sectional view taken from front to rear through the boiler shown in Fig. 1.

Fig. 3 is a fragmentary perspective view partially in section showing the structural features

2

and details of a water baffle embodied in said boiler.

Fig. 4 is an enlarged sectional view taken on line 4—4, Fig. 3.

5 Fig. 5 is a detached perspective view partially in section illustrating the structural features and details of a rear water tube located in the draft passage of the boiler of the present invention.

Fig. 6 is a sectional view taken on line 6—6, 10 Fig. 2.

Fig. 7 is a detached perspective view of a fire box embodied in the present invention; and

Fig. 8 is a partial vertical sectional view 15 through the boiler showing a modified construction and arrangement of certain parts thereof.

Referring now more particularly to the drawings, a steam or hot water boiler made according to the present invention comprises a pair of cylindrical lower headers 10 which are arranged in spaced parallel relation and horizontally disposed upon a base or foundation 11 of refractory material such as bricks. Cross-connected between the lower headers 10 are a plurality of inverted U-shaped water tubes 12, 13, 14, 15, 16, 17, 18 and 19, which are arranged in substantially equally spaced parallel relation longitudinally of the headers 10 and have their opposite ends respectively connected in fluid communication with the interior of the headers 10 as illustrated. At the mid-point of their bight or curved portion the water tubes 12 to 19 inclusive each have fluid connection with a relatively large top header 9 through vertical connecting pipes or tubes 20.

35 Within the area or space defined by the headers 10 and the inverted U-shaped tubes 12 to 17, inclusive, there is disposed a combustion chamber or fire box 21 which is assembled of relatively interlocking sections of refractory material 40 and adapted to rest upon a floor or bed 22 of similar material which is supported upon the base 11 with an intervening sheet of metal 23 as shown in Fig. 6. As illustrated, the fire box 21 has its lower side walls 24 shaped as indicated at 25 to conform to the curvature of the headers 10. An oil burner 26 may be employed to provide combustion within the fire box 21 and the hot combustion products leaving the fire box are directed laterally into contact with the upper portions of the tubes 12 to 17, inclusive, by means of an overlying horizontally disposed baffle 27 which is constructed and arranged in cooperation with the outwardly adjacent slightly 45 lower fire box top portions 28 to provide rela-

55

tively spaced oppositely directed openings 29 for the hot combustion products. The design of the fire box 21 is such that substantially complete oil combustion is obtained with a minimum supply of secondary air or oxygen.

As shown in Fig. 2 of the drawings, the fire box 21 does not extend the entire depth of the boiler and, in the illustrated embodiment of the invention, terminates just forwardly of the water tube 18. This particular tube 18 defines a transversely extending vertical water-leg or baffle, designated generally by the numeral 30 which serves to divide the interior of the boiler into fire box and draft flue portions, respectively.

With reference to Figs. 3 and 4 of the drawings, the water-leg or baffle 30 is formed by providing between the headers 10 a cross-connecting tube 31 and securing to the tube 18 and tube 31 at opposite sides thereof, a pair of suitably configured plates 32. These plates 32 may be secured to the tube 18 and tube 31 to provide a watertight chamber 33 therebetween by welding or the like as indicated at 34. Fluid intercommunication between the tubes 18 and 31 and the chamber 33 is effected by providing suitable openings in the tubes 18 and 31, for example, as indicated at 35. The plates 32 may be additionally supported by means of spacing studs or the like 36 secured therebetween.

With reference to Fig. 2 of the drawings, it will be observed that the boiler construction of the present invention provides a down-draft passage 37 for the products of combustion so that the hot combustion gases emanating from the laterally directed openings 29 of the fire box 21 sweep the upper portions of the adjacent tubes 12 to 17, inclusive, and the under portion of the top header 9 as the gases pass generally rearwardly through the boiler and over the top of the water baffle 30 whence they travel downwardly through the passage 37 to the flue opening 38 adjacent the bottom of the boiler, the path of travel of the combustion products being indicated generally by the arrows in Figs. 2 and 6 of the drawings. The provision of the water-baffle 30 serves not only to increase materially the water capacity of the boiler but provides for increased operating efficiency through provision of relatively lower stack temperatures.

In the illustrated embodiment of the invention and as previously stated herein, the water baffle 30 is formed in association with the tube 18 and hence the most rearward water tube 19 is disposed in the downdraft passage or duct 37 where it is swept by the hot combustion gases passing downwardly through said passage 37 to the flue connection or opening 38 at the bottom thereof and constitutes a boiler make-up water pre-heater 39.

Preferably the most rearward tube 19 constituting the pre-heater 39 is constructed and arranged as shown in Figs. 2 and 5 of the drawings. Thus, a pipe or tube 40 of pre-selected diameter and length is arranged vertically between the legs of the U-shaped tube 19 and has its upper end interconnected with the tube at the underside of the bight portion thereof as illustrated. Interconnected between the vertical tube 40 and the outwardly adjacent legs of the U-shaped tube 19 is a plurality of interconnecting branch tubes 41 arranged in substantially equally spaced parallel relation and declining outwardly from the central tube 40 to the legs of the U-shaped tube 19, for example, as shown in Fig. 5. By utilizing this construction for the most rearward tube 19 it will be apparent that the water capacity thereof

may be increased without increase in the overall dimensions of the space occupied thereby and while at the same time increasing the radiating surface area for heat exchange between the water within the tube 19 and the downwardly moving combustion gases. The number of branch tubes 41 employed in any given installation will depend, of course, upon the capacity and radiation surface required or desired.

This rearwardmost tube 19 constitutes the circulating return line from the top header 9 to the lower headers 10 and also has connected thereto adjacent the lower end of the tube 40 thereof a pipe 42 by means of which hot water supplied to an associated heating system from the top header 9 is returned for reheating and recirculation in the conventional manner or by means of which additional water may be admitted to the boiler as called for by the water level indicator or like device 43.

By disposing the rearwardmost tube 19 in the downdraft passage 37 of the boiler, the relatively cool water recirculating from top header 9 to the lower headers 10 and entering the boiler through the tube or pipe 42 as described serves to cool the hot combustion gases as they pass downwardly through the passage or duct 37 to the flue 38 thus resulting in relatively lower flue or stack temperatures. On the other hand, the heat exchange which takes place between the relatively cool water in the rearwardmost tube 19 and the hot combustion gases serves also to substantially preheat the water before it enters the lower headers 10 of the boiler. By this construction and arrangement, resulting in relatively lower stack temperatures and substantial preheating of the water entering the boiler headers 10, it will be apparent that the over-all efficiency of the boiler is materially increased and is quite high.

Furthermore, it will be obvious that the construction of the water tube 19 incorporating the central and branch tubes 40 and 41 may be employed and utilized in one or more of the water tubes 12 to 17, inclusive, to thereby increase the capacity of the boiler as required for different uses without increasing the over-all size and dimensions thereof.

A modification of the previously described construction is shown in Fig. 8 of the drawings wherein, in place of the water baffle 30 provided in conjunction with the tube 18, there is provided between the water tubes 18 and 19 a baffle member 44 of refractory material which conforms substantially to the shape of the tubes 18 and 19 and substantially fills the space therebetween. In all other respects the construction of the boiler is the same as previously described.

The boiler is encased within the usual heat-insulating material 45 at the front, rear and opposite sides thereof and the latter at its upper ends curves inwardly into engagement with the top header 9 of the boiler in the relation shown in Figs. 1 and 6 of the drawings. This insulation may be supported by suitable backing sheets 46 and the entire structure including the oil burner 26 may be enclosed by a sheet metal casing providing a pleasing external appearance in accordance with present day practice. Further in accordance with usual practice, the top header 9 preferably contains a domestic hot water heating coil 47 which may be connected and controlled to operate according to the usual so-called summer and winter hook-up, and the header 9 should be provided with the usual pressure gauge 48 and relief valve 49.

It is to be noted that the entire boiler, including the tubes 12 to 19, inclusive, baffle 30, make up heater 39 and headers 9 and 10 may be fabricated of steel and welded together to provide a relatively light and durable boiler construction which is characterized by its inexpensiveness to manufacture and efficiency in operation.

The boiler construction of the present invention also provides an oil-fired boiler of the down-draft type which embodies means for cooling the combustion gases passing to the stack to provide relatively lower stack temperatures while at the same time effectively pre-heating the make-up water entering and returning to the boiler for reheating and recirculation. The invention further provides a boiler construction which is constructed and arranged so that additional heating surface and water capacity may be added as required without increasing the size and dimensions of the boiler.

Apart from these features and characteristics of construction and operation the boiler of the present invention embodies a water baffle and make-up heater of distinct and novel construction, and provides generally a boiler which is highly economical and efficient in operation and use.

While certain embodiments of the present invention have been illustrated and described herein, it is not intended to limit the invention to such disclosure and changes and modifications may be made therein and thereto within the scope of the following claims.

I claim:

1. In a boiler of the character set forth comprising a casing structure, a pair of relatively spaced lower headers extending adjacent opposite sides of the casing in the lower portion thereof, an upper header extending longitudinally in the top portion of said casing centrally thereof with respect to said lower headers, a plurality of water tubes arranged in spaced relation longitudinally of said lower headers and interconnecting the same with said upper header, a baffle structure transversely of the boiler and extending vertically therein to a point spaced below said upper header and sub-dividing the interior of the casing into a forward combustion chamber and a rearward vertical passage communicating with said combustion chamber above said baffle structure, and a fire box disposed forwardly of said baffle structure between said lower headers and said water tubes and having in the opposite sides thereof openings inwardly offset from the side walls of said box, and directed laterally toward said water tubes so that combustion gases passing from said fire box are caused to sweep the water tubes arranged along opposite sides of said fire box.

2. In a boiler of the character set forth comprising a casing structure, a pair of relatively spaced lower headers extending adjacent opposite sides of the casing in the lower portion thereof, an upper header extending longitudinally in the top portion of said casing centrally thereof with respect to said lower headers, a plurality of water tubes arranged in spaced relation longitudinally of said pair of lower headers and interconnecting the same with said upper header, a baffle structure transversely of the boiler and extending vertically therein to a point spaced below said upper header and sub-dividing the interior of the casing into a forward combustion chamber and a rearward vertical passage communicating with said combustion chamber above

said baffle structure, said baffle structure being positioned longitudinally of said headers with respect to said water tubes so that at least the most rearward water tube is disposed in said vertical downdraft passage, and a fire box disposed forwardly of said baffle structure between said lower headers and said water tubes and having in the opposite sides thereof openings inwardly offset from the side walls of said box, and directed laterally toward said water tubes so that combustion gases passing from said fire box are caused to sweep the water tubes arranged along opposite sides of said fire box.

3. In a boiler of the character set forth comprising a casing structure, a pair of relatively spaced lower headers extending adjacent opposite sides of the casing in the lower portion thereof, a series of water tubes of inverted U-shape arranged in spaced relation longitudinally of said pair of lower headers with the ends of said tubes connected respectively to said headers, an upper header in the top portion of said casing spaced above said water tubes and connected to each thereof, a cross-connection between said lower headers in the plane of one of said water tubes, and plates secured in fluid-tight relation to opposite sides of said one of the water tubes and cross-connection and to said lower headers thereby enclosing the space defined therebetween to provide a transversely extending vertical water baffle sub-dividing the interior of the casing into a forward combustion chamber and a rearward vertical passage communicating with said combustion chamber above said water baffle, at least one of said cross-connections and one water tube having openings therein for supplying water to the interior of said baffle.

4. In a boiler of the character set forth comprising a casing structure, a pair of relatively spaced lower headers extending adjacent opposite sides of the casing in the lower portion thereof, a series of water tubes of inverted U-shape arranged in spaced relation longitudinally of said pair of lower headers with the ends of said tubes connected respectively to said headers, an upper header in the top portion of said casing spaced above said water tubes and connected to each thereof, a cross-connection between said lower headers in the plane of one of said water tubes, and plates secured in fluid-tight relation to opposite sides of said one of the water tubes and cross-connection and to said lower headers thereby enclosing the space defined therebetween to provide a transversely extending vertical water baffle sub-dividing the interior of the casing into a forward combustion chamber and a rearward vertical passage communicating with said combustion chamber above said water baffle, the water tube with which said baffle is associated being an intermediate one of said series so that at least the most rearward water tube is disposed in said vertical passage.

5. Apparatus as claimed in claim 3, wherein the baffle structure comprises a cross-connection between said lower headers in the plane of one of said U-shaped water tubes, and plates are secured in fluid-tight relation to opposite sides of said one U-shaped water tube and cross-connection and to said headers thereby enclosing the space defined therebetween to provide a water chamber, said water tube and cross-connection having openings therein communicating with the interior of said chamber.

6. In a boiler of the character described having a pair of headers, a water baffle comprising

an inverted U-shaped water tube having its ends connected respectively to said headers, a cross-connection between said headers in the plane of said water tube, and plates secured in fluid-tight relation to opposite sides of said water tube and cross-connection and to said headers thereby enclosing the space defined therebetween to provide a water chamber, at least one leg of said water tube and cross-connection having openings therein communicating with the interior of said chamber.
